W. H. YERKES.
RAIL CONNECTION.
APPLICATION FILED JULY 13, 1908.

Patented May 11, 1909.

UNITED STATES PATENT OFFICE.

WILMER H. YERKES, OF SHERIDANVILLE, PENNSYLVANIA.

RAIL CONNECTION.

No. 921,575.

Specification of Letters Patent.

Patented May 11, 1908.

Application filed July 13, 1908. Serial No. 423,246.

To all whom it may concern:

Be it known that I, WILMER H. YERKES, a citizen of the United States of America, residing at Sheridanville, in the county of Allegheny and State of Pennsylvania, have invented certain new and useful Improvements in Rail Connections, of which the following is a specification, reference being had therein to the accompanying drawing.

10 This invention relates to a rail connection, and the objects of my invention are, first, to provide a novel chair for supporting the confronting ends of two rails; second, to obviate the necessity of using a plurality 15 of bolts and nuts as a fastening medium for joints of two rails; third, to provide a novel connection that can be easily and quickly assembled for firmly holding the confronting ends of rails; and fourth, to provide a 20 simple and durable rail connection that will prevent lateral and vertical displacement of the confronting ends of two rails.

I accomplish the above objects by providing a novel chair adapted to support the 25 ends of rails, and in connection with the chair I use splice bars and locking members, these elements being secured together upon each side of the rails.

The detail construction entering into my 30 invention will be presently described and then specifically pointed out in the appended claims.

In the drawings: —Figure 1 is an end view of my rail connection, Fig. 2 is a plan of the 35 same, Fig. 3 is a perspective view of one of the locking members, and Fig. 4 is a perspective view of one of the splice bars.

In the accompanying drawings, 1 designates ties supporting rails 2, said rails having 40 their confronting ends arranged intermediate of the ties 1. Embracing the base flanges 3 of the rails is a chair comprising a base plate 4, and longitudinal vertical side walls 5 terminating in upper hook-shaped 45 edges 6. In connection with the chair I use splice bars 7, the splice bars resting upon the base flanges 3 and bracing the web portions and heads of said rails. The flange 8 of each splice bar is provided with a central opening 9, the object of which will presently appear.

For holding the splice bars 7 in position, I use locking members, each member comprising an angle bar 9^a, having the outer 55 edge thereof provided with a longitudinal enlargement 10, which is crescent-shaped

in cross-section and adapted to engage under the hook-shaped upper edges 6 of the side walls 5. The angle bars 9^a are provided with central openings 11 adapted to 60 align with the openings 9 of the splice bars 7, and passing through said openings are bolts 12, which extend between the confronting ends of the base flanges 3, and through openings 13 provided therefor in 65 the base plate 4. The bolts are retained in position by nuts 14 screwed upon the lower ends of said bolts. In order that the angle bars 9^a will be firmly held in position, I drill the openings 11, 9 and 13 at an inclination 70 toward the vertical axis of the rails, and in order that the nuts 14 will obtain a firm purchase upon the lower face of the base plate 4, said base plate is formed with a longitudinal recess having angular faces 15 at 75 right angles to the longitudinal axis of the openings 11, 9 and 13.

The upper hook-shaped edges of the walls 5 provide longitudinal grooves 16 conforming 80 in cross section to approximately 225 degrees of a circle, and the longitudinal enlargements 10 in cross section conform approximately to the same number of degrees, whereby after said enlargements have been 85 swung into the grooves 16, the hook-shaped edges 6 of the walls 5 will prevent vertical displacement of the locking members, and assist in holding said members in engagement with the splice bars 7. This arrangement of the enlargements 10 takes up all 90 lost motion and provides a snug and tight joint, the efficiency of which is increased by a load upon the rails. The enlargements 10 of the locking members are of greater length, than the angle bars 9^a and the hook-shaped 95 edges 6 of the chair, whereby the edges of the splice bars will be firmly held at each end of the chair.

My rail connection is constructed of strong and durable metal or material, and while in the drawings forming a part of this application there is illustrated the preferred embodiments of my invention, I would have it understood that the elements therein can be varied or changed as to shape, size, and manner of assemblage without departing 105 from the spirit of the invention.

Having now described my invention what I claim as new, is:—

1. In a rail connection, the combination, 110 with the confronting ends of rails, of a chair, said chair comprising a base plate having

vertical walls for embracing the base flanges of said rails, said walls terminating in hook-shaped upper edges having longitudinal grooves, splice bars bracing the webs and heads of said rails, said splice bars having central openings formed therein alining vertically with the confronting edges of said rails, locking members adapted to engage in the grooves of said hook-shaped edges for 10 bracing said splice bars, said members comprising angle bars having longitudinal crescent-shaped enlargements adapted to fit in said grooves, said angle bars having central openings formed therein adapted to align 15 with the openings of said splice bars and with openings formed in said base plate, bolts extending through said openings, and nuts screwed upon the lower ends of said bolts, substantially as described.

20 2. In a rail connection, the combination with the confronting ends of rails, of a chair, said chair comprising a base plate having vertical walls for embracing the base flanges of said rails, said walls terminating in hook-

shaped upper edges having longitudinal 25 grooves, splice bars bracing the webs and heads of said rails, said splice bars having central openings formed therein alining vertically with the confronting edges of said rails, locking members adapted to engage 30 in the grooves of said hook-shaped edges for bracing said splice bars, said members comprising angle bars having longitudinal crescent-shaped enlargements adapted to fit in said grooves, said angle bars having central 35 openings formed therein adapted to align with the openings of said splice bars and with openings formed in said base plate, and means for locking said members, splice bars and chair together upon the confronting 40 ends of said rails.

In testimony whereof I affix my signature in the presence of two witnesses.

WILMER H. YERKES.
